(57) **CLAIM**

The ornamental design for a water flosser, as shown and described.

DESCRIPTION

FIG. 1 is a front and bottom perspective view of a water flosser, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and

FIG. 8 is a bottom plan view thereof; and,

FIG. 9 is an enlarged view of FIG. 2.

The dashed broken lines depict portions of the water flosser that form no part of the claimed design. The dash-dot broken lines define the bounds of the enlargement and form no part of the claimed design.

1 Claim, 9 Drawing Sheets
